J. M. GOLDEN

GERMICIDE TANK

Original Filed July 21, 1922

Inventor:

J. M. Golden.
by Hazard & Miller

Attest.

UNITED STATES PATENT OFFICE.

JAMES M. GOLDEN, OF PASO ROBLES, CALIFORNIA.

GERMICIDE TANK.

Application filed July 21, 1922, Serial No. 576,581. Renewed March 18, 1925.

To all whom it may concern:

Be it known that I, JAMES MARTIN GOLDEN, a citizen of the United States, residing at Paso Robles, in the county of San Luis Obispo and State of California, have ⁵ invented new and useful Improvements in Germicide Tanks, of which the following is a specification.

My invention relates to hair cleaning apparatus and is a continuation in part of my ¹⁰ copending application Serial No. 432,566, filed December 22, 1920.

A purpose of my present invention is the provision of a hair cleaning apparatus ¹⁵ including a receptacle or tank designed to receive the matter removed from the scalp and provided with filtering means for allowing the passage of air through the receptacle and yet retaining the particles within the receptacle. Furthermore, my invention provides a deflecting chute for the discharge end ²⁰ of the receptacle, and means for facilitating the fumigation of the receptacle.

I will describe one form of hair cleaning apparatus embodying my invention and will ²⁵ then point out the novel features thereof in claims.

In the accompanying drawings,

Figure 1 is a view showing a vertical ³⁰ longitudinal section of one form of apparatus embodying my invention assembled for operation.

Fig. 2 is a view similar to Fig. 1 with the apparatus assembled for fumigation.

Fig. 3 is an enlarged sectional view of the ³⁵ connecting member comprised in the apparatus.

Figs. 4 and 5 are sectional and plan views, respectively, of a portion of the receptacle and the means for securing the door shown ⁴⁰ in Fig. 2.

Fig. 6 is a fragmentary view showing in ⁴⁵ side elevation one of the filtering units comprised in the apparatus shown in the preceding views.

Fig. 7 is a fragmentary sectional view of the abutment frame and the means for securing the filtering units in position within the receptacle.

Similar reference characters refer to ⁵⁰ similar parts in each of the several views.

Referring specifically to the drawings, my invention, in its present embodiment, comprises a receptacle designated generally at R, one end of which is closed and provided ⁵⁵ with a relatively small opening in which is

threadedly fitted a nipple 15 provided with a head 16 forming a valve seat for a valve 17 hingedly supported upon a head indicated at 18. Bushings 19 are secured in surrounding position with respect to the opening, and the nipple 15 threadedly engages these bushings as clearly shown in Fig. 1. Upon the projecting end of the nipple 15 a conduit 20 is adapted to be removably fitted, and this conduit is in communication with ⁶⁰ a pump 21 operated by a motor 22. The pump 21 operates to create a suction within a flexible pipe 23 to which a brush nozzle (not shown) is adapted to be connected.

Contained within the receptacle adjacent ⁷⁰ its open end is a filtering member made up of a plurality of filtering units, with each unit comprising, as shown in Fig. 6, a pair of frames 24 secured together by means of pins 25 and between which are arranged screens 26 embracing a sheet of cloth 27. The several units are adapted to be secured side by side within the receptacle by an abutment frame 28 suitably secured within the receptacle and carrying rods 29 threaded ⁸⁰ to receive wing nuts 30. The several frames 24 are formed with registering openings to permit the insertion of the rods 29, and after the frames have been applied to the rods they are firmly secured within the receptacle ⁸⁵ by the application of the wing nuts 30.

Under operating conditions, the filtering end of the receptacle receives a deflecting chute designed for the purpose of deflecting the air or any solid particles which may ⁹⁰ percolate the filtering member upwardly from the receptacle. This chute, in the present instance, comprises a frame 31 adapted to be secured within the open end of the receptacle by pins 32 carrying wing ⁹⁵ nuts 33. As shown in Figs. 4 and 5, the pins 32 engage within slots 34 formed in the end of the receptacle so that when the nuts are tightened, the frame will be securely held therein. The frame 31 carries side plates 35 connected by a curved plate 36, the latter being secured to the side plates and to the frame 31 in a manner clearly shown in Fig. 1.

When the apparatus is in inactive position, it is desirable that the receptacle be fumigated, and to this end a tubular connecting member 37 is slidably fitted within the nipple 15 so as to maintain the valve 18 in open position. The member 37 carries a cap 38 ¹⁰⁵ designed to have snug engagement with the

outer bushing 19 and to thereby provide an air tight joint between the member and nipple. A pipe 39 connects the outer end of the member 37 with a container 40 in which a suitable fumigating chemical is stored. The open end of the receptacle is adapted to be closed by a door 41 secured to the receptacle in the same manner as the frame 31.

In the operation of the apparatus, the pump 21 operates to create a suction within the pipe 23, and the particles collected are conducted to the receptacle through the conduit 20. The filtering member operates to retain the solid particles within the receptacle at the same time allowing of the passage of air from the receptacle into the chute. It is to be particularly noted that by virtue of the mounting of the valve 17 it gravitates to closed position when the pump is not operated so as to seal the contents of the receptacle.

When the apparatus is not in operation and it is desired to fumigate the same, the conduit 20 is disconnected from the nipple 15, and the connecting member inserted into the latter. The chute is removed from the open end of the receptacle and the door 41 substituted so that the open end of the receptacle is now closed. By connecting the pipe 39 to the connecting member 37 the fumes from the chemical in the container 40 pass into the receptacle so as to thoroughly fumigate the receptacle as will be understood.

Although I have herein shown and described only one form of hair cleaning apparatus embodying my invention, it is to be understood that various changes and modifications may be made herein without departing from the spirit of the invention and the spirit and scope of the appended claims.

I claim as my invention:

1. In a cleaning apparatus, a receptacle hav-

ing a closed end and an open end, a nipple fitted in the closed end of the receptacle and having a head constituting a valve seat, a valve hingedly supported on the seat and normally occupying a closed position to close the end of said nipple, a conduit connected to the nipple, means for creating a suction inwardly of the conduit, a filtering member 50 in the receptacle, and a chute removably fitted in the open end of the receptacle for deflecting the air and solid particles upwardly from the receptacle.

2. In a cleaning apparatus, a collecting receptacle open at one end, an air filter therein, a suction line for forcing air into said receptacle, means for discharging from said suction line into said receptacle, a check valve permitting the air to enter the receptacle, but preventing the air to pass in the opposite direction.

3. In combination, a collecting tank having an open end, a filter therein, a suction line, a discharge line from said suction line to said tank, a normally closed valve for the discharge line, and a connection received over the discharge line and arranged to open said valve.

4. In a cleaning apparatus, a receptacle 70 having an open end, and a filtering member within the open end of the receptacle comprising an abutment frame within the receptacle, a plurality of filtering units including frames arranged side by side within the receptacle, with one of the frames abutting the abutment frame, rods secured to the abutment frame and extending through the filtering frames, and means for securing the filtering frames against displacement from said rods.

In testimony whereof I have signed my name to this specification.

JAMES M. GOLDEN.
